UNITED STATES PATENT OFFICE

2,417,268

INDICATING MEANS FOR THERMAL
CIRCUIT INTERRUPTERSAlric H. Powell, Yeadon, Pa., assignor to General
Electric Company, a corporation of New York

Application June 3, 1944, Serial No. 538,575

4 Claims. (Cl. 200—121)

1

My invention relates to improvements in electric circuit interrupting devices such as fuses for protecting high voltage electric circuits. Specifically my invention is an improvement on my prior Patent 2,343,224, granted February 29, 1944, and assigned to the same assignee as the present application.

High voltage fuses which consist in the main of a fusible element in the form of one or more conductors of suitable metal such as silver or zinc embedded in a granular, inert, or refractory arc extinguishing material of high dielectric strength such as sand, or relatively finely divided quartz, are known. Such power fuses, usually called fuses of the enclosed type or current limiting fuses, are capable of interrupting currents of large magnitude without noise, discharge of liquid or solid particles or production of gases which must either be discharged to atmosphere or dissipated in a high pressure chamber.

It is an object of my invention to provide a new and improved circuit interrupting device of the above mentioned type which is simple and inexpensive to manufacture, sturdy in construction and very efficient in operation.

It is another object of my invention to provide a high voltage fuse of the sand filled type which may be manufactured and assembled at a much lower cost than similar devices used heretofore, and yet which gives superior operation from an interrupting standpoint.

Further objects and advantages of my invention will become apparent as the following description proceeds and the features of novelty which characterize my invention will be pointed out with particularity in the claims annexed to and forming a part of this specification.

For a better understanding of my invention reference may be had to the accompanying drawing in which Fig. 1 is a sectional view of an exemplary form of high voltage fuse constructed in accordance with my invention and showing the indicating means for the fuse in the nonindicating position; Fig. 2 is a view, partly in section, of a portion of the fuse in Fig. 1 showing the indicator in the position it would assume upon rupture of the fusible element; Fig. 3 is a sectional view taken on line 3—3 of Fig. 1; Fig. 4 is a perspective view of the indicator housing associated with the fuse rotated 90° with reference

2

to Fig. 1, and Fig. 5 is a top view of the indicator housing of Fig. 1.

Although it will be evident that certain parts of the present invention may be practiced to advantage with different types and forms of electric fuses, the invention lends itself most advantageously to practice with the enclosed type of fuse such as is disclosed, for example, in United States Letters Patent 2,294,132, granted August 10, 1942, upon an application of C. L. Schuck and assigned to the same assignee as the present application, wherein the fusible conductor is shown as being enclosed in a tubular casing of suitable insulating material and surrounded by or embedded in a pulverulent or sandy arc quenching material.

Referring now to the drawing, I have illustrated an electric fuse device which has a housing structure or casing 1, of open ended tubular form constructed of suitable insulating material such as glass, porcelain, fiber, or the like. Within tubular housing 1 there is provided an elongated insulating support or core 2, comprised of high heat-resisting ceramic or other suitable material. This core extends longitudinally of casing 1 and serves to support a current interrupting element 3 which is spirally wound on the core, as is clearly indicated in Fig. 1. Although the current interrupting element 3 of the illustrated device comprises only a single conductor, it is common in the construction of such fuses which are generally referred to as of the current limiting type, to employ one or more main conductors depending upon the current rating. This is for the reason that it has been found that most effective limiting action is produced when conductors of very thin cross section are employed. Hence, where the current rating demands a relatively large total cross section it is desirable to divide this total cross section into a number of parallel connected conductors having thin cross section, such as a plurality of fine wires. The interior of casing 1 around core 2 is filled with an inert, granular arc quenching material 4, such as sand or pulverized quartz which embeds the current interrupting element 3. As will be seen from the sectional view of Fig. 3, the core 2 is of generally star-shaped form in that it has a plurality of longitudinally extending fins or ribs 5. Although the illustrated core 2 has four such

fins 5, a core having more or less than four fins may be employed depending upon the rating and size of the particular fuse. The advantage of a star-shaped core is that the current interrupting element 3 touches the core 2 only at spaced points so that the maximum length of the element is exposed to the filler material 4. Spirally winding the interrupting element 3 on core 2 permits the installation of an element of relatively great length in a casing of practical dimensions.

In order to close the ends of tubular housing or casing 1, I provide suitable end caps or closure members 6 and 7, which are generally saucer-shaped. End cap 6 illustrated as the upper end cap, is substantially identical with the lower end cap 7 except that the latter is provided with a recessed opening which will be described hereinafter.

As shown in the drawing, these end caps 6 and 7 are each provided with an interlocking means illustrated as an off-set shoulder 8 and they are adapted to be held in sealed relationship with tubular housing or casing 1 by metallic ferrules 9, which are molded or die cast around the ends of tubular casing 1 so as to envelope the off-set shoulders 8 of end caps 6 and 7, while permitting the major portion of the end caps to remain exposed. As will be described hereinafter, the metallic ferrules 9 are electrically connected with the circuit interrupting element 3 and consequently provide the upper and lower terminals of the fuse device. Although I have specifically shown the interlocking means as comprising an off-set shoulder 8, it should be understood that such interlocking means might equally well consist of pin pricks, corrugations, knurlings, or grooves of some sort. Furthermore, the inherent irregularities of the end caps 6 and 7 might be depended upon for obtaining the desired mechanical grip. The construction of the end caps and the die cast ferrules is not my invention but is disclosed and claimed in United States Letters Patent 2,387,937, Serfling et al., assigned to the same assignee as the present application.

Since the major portion of the end caps 6 and 7 remain exposed after the molding or die casting operation, suitable indicia may be provided on this exposed surface of the end caps to set forth the fuse size or any other pertinent information.

Lower end cap 7, as was mentioned above, is provided with a recessed hole or opening 10, into which is fastened a spring support 11 as by peening over the ends thereof, as is clearly shown in Figs. 1 and 2. This spring support 11 has an outside thread to which may be threadedly mounted a tubular target or indicator housing 12 constructed of fiber, glass or other suitable insulating material. Reciprocatingly mounted within tubular housing 12 and adapted to extend out of opening 10 in lower end cap 7, is an indicator or plunger 13 which is provided with an enlarged portion 14. A suitable compression spring 15 mounted in spring support 11 and bearing against enlarged portion 14 of indicator 13 constantly biases plunger or indicator 13 to the indicating position shown in Fig. 2.

In order to maintain plunger or indicator 13 in the nonindicating position shown in Fig. 1, the upper end of tubular indicator housing 12 is substantially closed except for a small central opening 16 extending along the axis of tubular indicator housing 12. A suitable tension spring

17 has one end thereof fastened to the plunger or indicator 13 as indicated at 18, while the other end thereof is fastened to a strain or supporting wire 19 which in turn extends through the small opening 16. The portion of strain wire 19 extending outside of indicator housing 12 is passed through small openings 20 in the upper end of indicator housing 12, which openings are arranged substantially perpendicular to the opening 16, and is twisted about itself so as to place sufficient tension on tension spring 17 to maintain the indicator 13 in the nonindicating position shown in Fig. 1. When tension spring 17 is stressed as shown in Fig. 1, the plunger 13 is held in a floating condition with a substantially constant force applied to strain wire 19, whereupon jarring or rough handling of the fuse device will not harm or cause rupture of strain wire 19. It will be obvious that compression spring 15 must be a weaker spring than tension spring 17. With the floating construction of plunger 13 described above, a much weaker strain wire 19 may be used without danger of stretching or rupturing to permit the indicator or plunger 13 to move to the indicating position shown in Fig. 2. I have discovered that without the use of tension spring 17, strain wire 19 must be able to withstand ten or more times the force of spring means 17 to prevent movement of the plunger 13 out of its nonindicating position merely due to normal handling of the fuse device. The floating arrangement of the indicator is disclosed and claimed in my prior Patent 2,343,224, referred to above.

It is desirable to obtain operation of the indicator comprising plunger 13 in response to rupture of the fuse link or circuit interrupting element 3 and to this end I provide an indicator wire 21 which is also wound on star-shaped core 2 in a spiral manner and preferably between turns of the circuit interrupting or fusible element 3. As will be described hereinafter, the upper end of the indicator wire 21 is electrically connected to upper terminal ferrule 9. The lower end of indicator wire 21 is passed through small openings 22 in indicator housing 12. These small openings 22 are arranged parallel to openings 20 and displaced from the axis of indicator housing 12 by a certain distance so that when indicator wire extends through openings 22 a gap 23 is provided as is clearly shown in Fig. 4, between strain wire 19 and indicator wire 21. I have found that a gap of $\frac{1}{32}$ of an inch is satisfactory for the purpose to be described hereinafter. By virtue of the gap 23, clearly indicated in Fig. 4 between strain wire 19 and indicator wire 21, current is normally prevented from flowing between upper and lower ferrules 9 through indicator wire 21. If, however the circuit interrupting or fusible element 3 should be ruptured due to excessive current flowing therethrough, a potential is established across the gap 23 between indicator wire 21 and strain wire 19, which potential produces arcing across the gap with consequent rupture of strain wire 19 either by melting due to current flowing therethrough or by the direct heat of the arc which will cause rupture even at very low currents.

In order to cause proper operation of the fuse device described above on long continued over-load conditions, it is desirable to provide one or more thermal chambers such as are generally indicated at 24 in Fig. 1. Preferably these thermal chambers may be constructed in accordance with

those disclosed and claimed in my prior patent referred to above.

In constructing or assembling the fuse device of Fig. 1 the indicator housing 12 is first fastened to lower end cap 7, as is clearly described above with the plunger element suitably maintained in the non-indicating position. The star-shaped core 2 is then mounted next to the indicator housing 12 and is bound to the tube by a binder comprising a plurality of turns of wire, cord, or the like, indicated at 25 in Fig. 1. Before the core 2 is fastened to indicator tube 17 it has applied thereto at either end thereof terminal elements 26 substantially identical with the terminal elements disclosed and claimed in the above mentioned Schuck patent. These terminal elements comprise a looped portion 27 for fitting around one of the ribs 5 of core 2. The lower terminal 26 is first suitably welded to the lower end of fusible or interrupting element 3 and is securely bound to core 2 by the binder 25 which also holds core 2 to housing 12. Then the fusible element 3 is wound on the core with the upper end thereof having been welded to upper terminal 26. This upper terminal 26 is securely bound to core 2 by a plurality of turns of wire indicated at 28. Each of the terminals 26 is provided with an extension 29 which is adapted to extend outside of casing 1 so as to be enveloped by the molded or die cast ferrules 9 and, consequently, electrically connected thereto. The target element or indicator wire 21 is then passed through the openings 22 of indicating housing 12 and is twisted back upon itself to securely fasten it within openings 22. This indicating wire is then wound spirally on core 2 with its turns between the turns of the main circuit interrupting element 3, and the upper end of the indicator wire is fastened to the plurality of turns of wire forming the binder 28 for holding upper terminal 26 to core 2. At this stage preferably the holes 16, 20 and 22 in the indicator housing 12 are filled with a suitable cement to prevent the arc quenching material from escaping through these openings.

It will be observed then, that the lower end cap 7, the indicator housing 12 and associated indicator parts, the core 2 with the fusible element and indicator wire wound thereon, and the upper and lower terminals 26 fastened thereto, comprise a sub-assembly of the fuse device which may be placed in the tube or housing 1 so that the latter may be filled with granular material while the upper end cap 6 is removed therefrom. As soon as the housing 1 is filled with the granular arc quenching material the upper end cap 6 is placed into position and the fuse device is placed in a die casting machine whereupon the ferrules 9 are cast into place completely sealing the unit and providing the ferrules for the fuse device.

With my improved construction described above it is possible to preassemble a number of the elements into a sub-assembly which is easily handled without getting the elements out of place or damaging the main fusible element or the indicator wire. Thus the fuse device of my invention, while being simple in construction, greatly simplifies the manufacturing processes with consequent cost reduction.

Although I have elected to describe and illustrate herein a preferred embodiment of my invention as employed in a fuse device as well as the process of construction thereof, it is contemplated that other applications of my invention to fuses or like electrical devices other than the par-

ticular form illustrated, will suggest themselves to those skilled in the art. It is intended that such other applications or modifications as do not depart from the true spirit and scope of my invention will be covered by the appended claims.

What I claim as new and desire to secure by Letters Patent of the United States is:

1. In a circuit interrupting device having an interrupting element including a conductor spirally wound on an insulating support having longitudinally extending ribs for maintaining the conductor in spaced relation to a central body portion of the support, an indicating means for said device including a housing therefor, means for fastening said indicator housing to said insulating support, an auxiliary fusible element within said housing and attached thereto, and a cooperating auxiliary conducting element spirally wound on the insulating support intermediately of the turns of said conductor and having a portion passing through said housing to define therein a gap between such portion and said auxiliary fusible element.

2. In an electric circuit interrupting device including an insulating casing, an end cap for closing one end of said casing, an indicator housing extending longitudinally within said casing and supported from said end cap, a longitudinally ribbed insulating support in said casing having one end thereof engaging said end cap, means for holding said housing end cap and support as a unitary assembly, a pair of terminals one supported from each end of said support and each having a portion thereof extending outside of said casing, a circuit interrupting element including a conductor spirally wound on said support and interconnecting said terminals, an auxiliary fusible element within said housing and attached thereto, a cooperating auxiliary conducting element spirally wound on said support intermediately of the turns of said conductor and having a terminal portion passing through said housing to define therein a gap between such portion and said auxiliary fusible element an inert granular arc extinguishing material within said casing embedding said conductor and the part of said auxiliary conducting element outside of said housing, an end cap for closing the other end of said casing, and a ferrule of conducting material at each end of said casing for sealing the casing and enveloping the portions of said terminals extending outside of the casing so as to be electrically connected to said conductor.

3. In an electric circuit interrupting device the combination with an insulating enclosing casing, a fusible element therein, an indicator for indicating operation of said circuit interrupting device comprising a housing of insulating material supported from one end of said enclosing casing, an auxiliary fusible element within said housing and attached thereto, and a cooperating auxiliary conducting element arranged outside of said housing and having a terminal portion passing through the housing to define therein a gap between such portion and said auxiliary fusible element.

4. In an electric circuit interrupting device, the combination with an enclosing casing, a fusible element therein, means for supporting said fusible element in said casing, an indicator for indicating operation of said circuit interrupting device comprising a housing supported within said casing from one end thereof, an auxiliary fusible element within said housing and attached there-

to, an auxiliary conducting element arranged within said casing outside of said housing and having a terminal portion passing through the housing to define therein a gap between such portion and said auxiliary fusible element; means for uniting said housing and said supporting means as a unitary assembly; an end cap for said enclosing casing; and means including said housing for mechanically securing said supporting means to said end cap.
